UNITED STATES PATENT OFFICE.

CHARLES AUGUST DEUSCHER, OF NEW YORK, N. Y.

HORSE-OVERSHOE.

1,120,455.

Specification of Letters Patent.

Patented Dec. 8, 1914.

Application filed April 14, 1914. Serial No. 831,724.

To all whom it may concern:

Be it known that I, CHARLES A. DEUSCHER, a citizen of the United States, and a resident of the city of New York, borough of the Bronx, in the county of the Bronx and State of New York, have invented a new and Improved Horse-Overshoe, of which the following is a full, clear, and exact description.

This invention relates to farriery, and has particular reference to horseshoe attachments.

Among the objects of the invention is to carry forward and improve the novel features of invention disclosed in my previous application filed April 4, 1913, Serial No. 758,830. In this present invention, therefore, I provide a horse overshoe plate of peculiar and simple construction, the same having secured thereto in a rigid permanent manner a plurality of lugs or ears serving as connecting means for the overshoe.

Another object of the invention is to improve the hanger mechanism including the straps for detachably securing the overshoe to the horse's hoof.

A still further object is to improve the means for securing the grippers to the overshoe plate.

The foregoing and other objects of the invention will hereinafter be more fully described and claimed and illustrated in the drawings forming a part of this specification in which like characters of reference indicate corresponding parts in all the views, and in which—

Figure 1 is a perspective view of a preferred form of this invention shown as applied to a horse's hoof in lifted position; Fig. 2 is a plan view of the overshoe plate and pivoted grippers, the hanger means being omitted; Fig. 3 is a plan view of the device complete, showing the relation of the parts substantially as when applied to the hoof; and Fig. 4 is a transverse sectional detail on the line 4—4 of Fig. 2.

The several parts of the device may be made of any suitable materials, and the relative sizes and proportions, as well as the general design of the mechanism, may be varied to a considerable extent without departing from the spirit of the invention hereinafter more fully described and specifically claimed.

Referring more particularly to the drawings, I show at S any suitable form of ordi-

nary horseshoe either with or without calks and with or without a flexible heel pad. The shoe S or the equivalent will be connected to the horse's hoof in any well known or approved manner, the same constituting no part of this invention *per se*. The shoe illustrated, however, is provided with a toe calk c and heel calks c'.

At 10 I show my improved form of overshoe plate, the same being substantially flat but provided with an upwardly projecting lug 11 adapted to engage in the rear of the toe calk c or back of the toe portion of the main part of the shoe S. The bottom surface of the plate 10 is preferably smooth and unbroken, but the toe portion of the plate is provided with a backwardly projecting recess or indentation 12 to accommodate the usual shoe calk c when used. The upper surface, however, of the plate 10 is provided with pairs of oppositely arranged notches 13 arranged preferably adjacent the bottom of the main shoe and into which are adapted to be forced the prongs 14 of peculiar forms of pivoted grippers 15 and 16. These grippers are made of solid metal drop forged, cast malleable or otherwise formed so that in the event of wearing out of one or more of the grippers, others may be put into their place by swaging, crimping or otherwise, the prongs 14 being bendable for introduction into the notches 13.

I prefer to employ three or more of the grippers on each side of the shoe, and the grippers 15 at the sides of the shoe are preferably cruciform on the bottom so as to resist slipping in any direction. The grippers 16, while having the same general characteristics as the others, may be in the form of the letter I so as to provide ample gripping virtue and yet not materially damage city pavements.

At 17 I show a pair of lugs extending forwardly from the shoe plate 10 on each side of the toe, said lugs being formed preferably integral with the plate and strong enough to resist the strains or impacts to which they may be subjected in all practical operation. Secured to each of the lugs 17 is a hanger 18 having one end extending around the lug and having at its upper end a loop 18'. When the horseshoe is provided with heel calks, the plate 10 may be fitted snugly against the rear faces thereof, whereby the tendency of said plate to slide rearwardly will be resisted. The hangers 18, however,

are adapted to bear against the edges of the main shoe and the horse's hoof for the purpose of resisting such tendency when the attachment is applied to a shoe or pad without such heel calks.

The means for detachably securing the overshoe to the horse's hoof preferably includes a flexible band or strap 19 which may be permanently connected at one end to one loop 18' and passed thence through a loop or keeper 20 either formed integral with or secured to the side of the plate 10 near its heel, the strap thence passing in a substantially flat manner across the rear of the horse's frog and thence passing in like manner through a similar keeper 20 on the opposite side of the plate, and thence the strap 19 passes to the loop 18' of the opposite hanger. The device now under consideration may either be made for or fitted to a horse's hoof or ordinary shoe, or may be made in various sizes whereby the strap 19 will be placed in the position above set forth and connected permanently to the loops of the hangers. The hangers also being permanently connected to the lugs 17 of the plate are always ready for application, the hangers being free to swing around the lugs 17 in removing the attachment from or placing it upon the hoof. A second strap 21 extends across the front part of the hoof from one loop 18' to the other and serves in this connection to tighten the strap 19 and thereby securing the overshoe attachment rigidly in position. Under certain conditions the strap 21 might extend entirely around the hoof and take the place of the strap 19, but from my experience with this device, I prefer to employ the two straps as indicated. A buckle 22 of any suitable construction enables me to grip the strap 21 at any point to which it may be drawn and there fastened until it is desired to remove the overshoe.

Having thus described my invention, I claim as new and desire to secure by Letters Patent:—

1. The herein described horse overshoe comprising a plate having a pair of forwardly extending lugs rigidly secured thereto and having axes substantially radial with respect to the plate, a pair of hangers pivoted to said lugs and movable around the axes of the lugs into engagement with the front part of the hoof, said hangers each having a loop at its upper end, and flexible

strap means coöperating with said hanger loops and extending around the horse's hoof to detachably secure the horse overshoe in position.

2. In a device of the kind set forth, the combination with a main shoe, of an overshoe plate, gripping devices secured to the plate, and projecting downwardly therefrom, a pair of hangers movably connected to the front part of the plate and adapted to bear against the front part of the hoof and main shoe, a pair of rigid keepers secured to the sides of the plate and extending upwardly therefrom in approximately the same horizontal plane as the main shoe, and flexible strap means extending around the hoof coöperating with said hangers and keepers to detachably secure the overshoe in position.

3. In a horse overshoe, the combination of a plate, gripping devices secured thereto and extending downwardly therefrom, a pair of hangers movably connected to the front part of the plate and adapted to co-operate with the front part of the hoof, a pair of keepers connected to the sides of the overshoe plate adjacent the heels thereof, a flexible strap extending across the back portion of the hoof above the shoe, thence through said keepers and thence to the hangers where the ends of the strap are connected, and a second strap extending across the front of the hoof from one hanger to the other and serving to bind the overshoe detachably in place.

4. As an article of manufacture, the herein described plate for a horse overshoe comprising curved side members adapted to conform substantially to a main shoe, a front cross bar having a rearward depression formed integral with the side members, a pair of integral lugs extending substantially radially from the front ends of the side members, and a pair of rigid keepers formed integral with the outside edges of the side members and projecting upwardly slightly therefrom and lying in a plane substantially parallel with the upper surface of the plate.

In testimony whereof I have signed my name to this specification in the presence of two subscribing witnesses.

CHARLES AUGUST DEUSCHER.
